UNITED STATES PATENT OFFICE.

WILLIAM C. HABBERLEY, OF LYNN, MASSACHUSETTS.

SHOE.

Application filed November 4, 1921. Serial No. 512,304.

To all whom it may concern:

Be it known that I, WILLIAM C. HABBERLEY, a citizen of the United States, residing at Lynn, in the county of Essex and 5 State of Massachusetts, have invented certain new and useful Improvements in Shoes, of which the following is a specification.

This invention relates to shoes, and more particularly to shoes worn when walking or 10 exercising where the intense activity of the wearer causes frequent stress or bending action at the joints between the toes and the ball of the foot, and has for one of its objects to provide in a manner as hereinafter set 15 forth, a vamp attachment or a shoe provided with a vamp attachment for the purpose of reinforcing the shoe where the greatest stress occurs, as well as for protecting the outside of the hallux, or great toe, between the two 20 joints, against sharp abrasion and chafing caused by the deep wrinkle in an ordinary shoe when bent forward and which occurs when the heel is raised while the toe is on the ground.

25 A further object of the invention is to provide, in a manner as hereinafter set forth, a vamp attachment or a shoe including a vamp attachment for the purpose referred to and with the vamp attachment formed of a 30 toe cap portion, a ball strap portion and a vamp guard integral with each other and formed from a one-piece flexible body, such as leather, and not only secured directly to the outer face of the vamp, but further secured to the sole of the shoe.

With these and other objects in view, the invention consists in certain novel features of construction as hereinafter shown and described and then specifically pointed out in 40 the claim, and in the drawings illustrative of the preferred embodiment of the invention:—

Figure 1 is a perspective view of a shoe with the improved attachment applied.

45 Fig. 2 is an enlarged transverse section on the line 2—2 of Fig. 1.

Fig. 3 is a view of the improved device before being applied to the shoe.

50 In walking and in many forms of athletic exercises, relatively heavy stress is produced at the joint between the ball and toe portions of the foot frequently resulting in fracturing the shoe material at these points. The toe of the shoe is also liable to come in violent contact with the ground or obstructions rising therefrom. Then again the inner or

contiguous portions of the shoe, or the parts of the vamp opposite the joint of the large toe, are liable to come in contact and abrade those portions, and to reinforce and protect 60 these exposed portions of the shoe is the principal object of the present invention.

A vamp attachment in accordance with this invention, for not only reinforcing the vamp of the shoe, but also for protecting the 65 outside of the hallux, great toe, between the joints thereof is formed from a flexible body, preferably leather, of vamp-like form and which is of a width to extend around the vamp of the shoe and of a length to inclose 70 the toe of the shoe and terminate at a point removed from the rear end of the shoe vamp. The said flexible body is formed with a cut-out portion to provide a ball strap positioned between and spaced from the inner end of the 75 shoe vamp and also spaced from the inner end of the toe of the shoe, and said ball strap extends laterally from the inner towards the outer side of said flexible body. The intermediate part of the edge of said cut-out portion is rounded and positioned at the inside 80 of the hallux, great toe, and provides means whereby the surplus material of the shoe upper will fold upwardly when the foot is bent forward. The rear edge of the flexible 85 body is secured throughout to the vamp, as at 15. The edge of the cut-out portion is secured throughout to the vamp, as at 17. The ball strap gradually increases in width from its inner towards its outer end. 90

The flexible body from which the attachment is formed is set up to provide a toe cap portion 10, a ball strap portion 11, and a vamp guard portion 12. The flexible body is formed of a single piece of material and when in position on the vamp 17 extends at 95 the inner side thereof so as to protect the vamp at the outside of the hallux, great toe.

The edge of the toe cap portion 10, as well as the outer edge of the vamp guard portion 12, and also the free end of the ball strap portion 11, is secured to the sole portion 13 of the shoe, in a well-known manner as illustrated in Figure 2, and as indicated at 14.

By this simple means an efficient toe cap, 105 a vamp guard, and a ball strap are produced without the necessity for sewed joints between the parts.

The attachment does not present objectionable projections or protuberances on the 110 shoe, while at the same time all the advantages of the toe cap, and ball strap features

22
are secured together with a "wear" section over the vamp opposite the large toe joint or at the point where the right and left shoe are liable to contact when in use in one single 5 tight fitting member.

The preferred embodiment of the invention is disclosed in the drawings and set forth in the specification, but it will be understood that modifications within the scope 10 of the claim may be made in the construction without departing from the principle of the invention or sacrificing any of its advantages.

Having thus fully described the invention, 15 what is claimed, is:—

In combination in a shoe; a vamp provided with a toe portion, a flexible combined protective and reinforcing member of vamp-like form inclosing said toe portion and ex-

tended upon said vamp, the rear edge of said member terminating at a point forwardly of the rear edge of the vamp, said member having a portion thereof constituting a vamp guard and further cut away laterally to provide a ball strap extending from the inner side of said vamp guard portion and further spaced throughout from the inner end of the toe portion and the rear edge of the vamp, the intermediate part of the edge of said cut-away portion being rounded, said member extended between the vamp and the sole, means for securing the member, vamp and sole together, and means for securing the exposed edges of said member throughout to the vamp.

In testimony whereof, I affix my signature hereto:

WILLIAM C. HABBERLEY.
